UNITED STATES PATENT OFFICE.

CALEB C. DULA, OF NEW YORK, N. Y., ASSIGNOR TO THE CONTINENTAL TOBACCO COMPANY, OF SAME PLACE.

DESIGN FOR A BOTTLE OR JAR.

SPECIFICATION forming part of Design No. 32,086, dated January 9, 1900.

Application filed December 15, 1899. Serial No. 740,478. Term of patent 14 years.

To all whom it may concern:

Be it known that I, CALEB C. DULA, a citizen of the United States, residing at New York city, county of New York, and State of New York, have invented and produced a certain new and original Design for a Bottle or Jar, fully described and represented in the following specification and the accompanying drawings, forming a part of the same.

In said drawings, Figure 1 is a perspective view of a bottle or jar embodying the design, and Fig. 2 is a cross-sectional view taken on line 2 of Fig. 1.

The leading feature of the design is the peculiar shape and configuration of the bottle as shown, the bottle being shaped in the form

of a horseshoe and having opposite sides substantially flat and formed with a depressed central portion A and a raised border portion B, shaped to represent a horseshoe, with the ends of the horseshoe pointing upward.

What I claim is—

The design for a bottle or jar substantially as shown and described.

In testimony whereof I have hereunto set my hand in the presence of two subscribing witnesses.

CALEB C. DULA.

Witnesses:

M. B. PHILIPP,
T. F. KEHOE.
